UNITED STATES PATENT OFFICE.

FRANCIS M. VANDERVOORT, OF PUEBLO, COLORADO, ASSIGNOR TO THE POSITIVE LOCK COMPANY, OF PUEBLO, COLORADO, A CORPORATION OF COLORADO.

LATCH.

Application filed August 28, 1923. Serial No. 659,779.

This invention relates to latches, particularly to latches used on the closures of vehicles, such as automobiles for instance, although it is to be understood that latches embodying the invention are adapted to other uses. The term latch used herein is understood to broadly include both latch and lock constructions.

Closures of vehicles such as automobiles are subjected to many strains and stresses so that it is very difficult to prevent movement of the closure member with relation to its supporting casing when the vehicle is operated and this relative movement of closure member and casing ordinarily results in annoying squeaking or rattling of the closure member and its fastening means, especially after the parts have become worn.

An object of the invention is to provide a latch which will securely fasten the closure member to which it is attached in its casing so that substantially all rattling of the closure member in its casing is prevented.

Another object of the invention is to provide a latch, in which substantially all play between the parts of the latch and between the latch and the cooperating keeper is prevented so that wear and rattling is substantially eliminated.

Other objects and features of the invention will be apparent from the following description taken in connection with the accompanying drawings which illustrate one form of the invention, but it is to be understood that the specific embodiment of the invention shown and described is merely one form chosen to explain the principles of the broad invention.

In the drawings,

Fig. 1 is a side elevational view of a latch and its cooperating keeper embodying this invention shown in the position which the parts occupy when mounted on the door and door jamb, respectively, of an automobile, parts of the door and door jamb being indicated by dotted lines,

Fig. 2 is an end view of the latch and its cooperating keeper looking to the right of Fig. 1,

Fig. 3 is a sectional view of the latch only taken on the line 4—4 of Fig. 1 looking in the direction of the arrows,

Fig. 4 is an end view of the latch only, and

Fig. 5 is a plan view of the keeper.

Broadly speaking, the invention comprises normally projecting latching means movable without longitudinal retraction to latched position within rigid cooperating keeper means, and means for retracting the latching means to unlatch the same.

Stated more specifically, the invention comprises latching means adapted to be projected and retracted on an axis extending longitudinally thereof, said latching means adapted to be projected and retracted laterally of the longitudinal axis of said latching means, said latching means normally held in laterally and longitudinally projected position and adapted to be laterally retracted to engage within cooperating keeper means and then laterally projected to hold the latching means against rattling in the keeper means, and means for retracting the latching means longitudinally to unlatch the same.

Referring to the drawings, 10 indicates generally the latch mounting or casing which may be of any suitable or desired shape to support the latching means and the operating means associated therewith. In the example illustrated, the mounting 10 comprises a base or back plate 11 provided with holes 12 to receive fastening devices such as screws for securing the latch to the door, indicated in dotted lines at D. Plate 11 has an angular extension 13 at one end constituting the front face of the latch casing or mounting and arranged to lie flush with the free edge of the door. The extension or front plate 13 is provided with an aperture 14 which affords a passage for the latching means B therethrough. In the present instance (see Fig. 4) the aperture 14 is substantially U-shaped in outline with divergent portions or indentations 14^a and 14^b leading into or opening into the main part of the aperture.

The latching means, indicated generally by B is supported and guided by a longitudinal bar 15 supported at the front end of the casing or mounting 10 by front plate 13 and at the rear end of the casing by a support 16 which in the present instance is formed by a lug or tongue cut or struck out from the back plate 11.

As seen in Fig. 3, the front end of bar 15 extends through aperture 14 and projects a short distance from the front end or face of the casing. The part of the bar which projects from the front end of the latch cas-

ing comprises a flat bead 17, a rounded bead 18 and a connecting web portion 19 while the major part of the bar 15 comprises the rounded bead 18 and the web portion 19 much reduced in width. Bead 17 of bar 15 is seated or supported in a notch 20 provided in front plate 13, the part of the web which projects from the front face of the latch casing abutting the front face of front plate 13 to prevent bar 15 from sliding into the casing. In the example illustrated, bar 15 is formed from a single sheet of metal stamped and bent to the desired shape, but it is obvious that it can be made in other ways, as by casting, for instance, and the exact shape may differ from that illustrated.

As previously stated, the latching means, indicated generally by B, is mounted on and supported by the bar 15. The latching means comprises two latching members or leaves 21 and 22 and an abutment member or bar 23. The latching members or leaves 21 and 22 have arcuate or curved portions 26 and 27 and substantially straight portions 24 and 25 respectively, each straight portion extending from the convex side of its arcuate or curved portion in a line corresponding substantially with the radius of the arc of its curved portion. The latch members 21 and 22 are supported on bar 15 so that the concave sides of the arcuate or curved portions 26 and 27 engage the rounded or circular bead 18, being held in engagement therewith by the slightly resilient substantially U-shaped abutment member or bar 23, the arcuate portions 26 and 27 being provided with slots or perforations 28 and 29 respectively, two in each arcuate portion, which receive tongues or lugs 30 formed on the longitudinal edges of abutment member or bar 23. It will thus be seen that latch members or leaves 21 and 22 swing or rotate about the bead 18 of supporting bar 15, the divergent straight portions 24 and 25 swinging toward and away from each other. It will also be noted that as leaves 21 and 22 rotate to separate the swinging ends of the straight portions, abutment member or bar 23 is moved away from the bead 18 and the longitudinal axis of the latching means. Latching members or leaves 21 and 22 are normally held in separated or laterally projected position by leaf spring 31, latching members or leaves 21 and 22 being provided with holes 32 which receive and support the ends of the spring. The curved portion of abutment bar 23 is provided with a slot 33 for receiving and supporting spring 31. As stated before, the latching means extends through the aperture 14 in front plate 13, the aperture being large enough to allow free movement of the leaves 21 and 22 and abutment 23.

Bar 15 not only supports latching means B for swinging movement, but also for slid-

ing movement. Normally the latching means extends through aperture 14 and projects from the front end of the latch casing, the latching bolt being held in this position by a spring 34 coiled about bar 15, one end of the spring engaging support 16 and the other end engaging bent ears or lugs 35 on the rear end of abutment member 23. Spring 34 presses abutment bar 23 against a pivoted retracting lever 36 which extends through a slot 37 formed in the curved side of abutment member 23. Retracting lever 36, which is pivoted at 38 to the latch casing, is in turn pressed against a cam or roll-back 39 pivoted at 40. It will thus be seen that the retracting lever 36 and cam or roll back 39 form means for limiting the projection of the latching means or bolt from the casing and that the pressure of spring 34 transmitted by abutment member 23 to pivoted 35 retracting lever 36 and roll-back 39 holds these parts against rattling. A plate 41 cooperates with base or back plate 11 to house and support the retracting mechanism.

The outer end of the bolt or latching means B normally projects from the free edge of the door and when the door is swung to close it, the projecting end of the bolt engages and is retained by suitable keeper means 42 mounted on the door jamb J. The keeper means or strike plate 42 comprises a plate or block which may be of rectangular shape secured so as to be flush with the edge of the door jamb by suitable fastening means inserted through holes 43. The keeper or strike plate 42 is cut or stamped out to provide an irregular shaped opening 44 to receive the leaves and abutment bar comprising the latching means, said opening comprising a tapering entrance portion 45 leading from one edge of the keeper plate, a constricted neck portion 46 and an enlarged or reentrant portion 47. The restricted or neck portion 46 of the opening 44 is made large enough for the abutment bar 23 to pass through but too small for the leaves 21 and 22 to pass through in their spread open or laterally projected position. In swinging the door to latched position, the longitudinally projecting latching means strikes the keeper 42, the spread open or laterally projecting leaves 21 and 22 striking the tapering entrance portion 45, the leaves being forced together or laterally retracted. When the leaves are forced together or laterally retracted, the abutment member or bar 23 is also moved laterally toward the supporting bar 15. Lateral retraction or swinging together of the leaves continues until after they pass the constricted neck portion 46 of the keeper, the leaves then entering the enlarged or reentrant portion 47 of the opening 44. Just as soon as the straight ends of the leaves enter the enlarged or wider part of the opening, the

leaves are laterally projected by spring 31, the straight ends of the leaves flying outward until they come into engagement with the curved edges of the opening, abutment 5 bar 23 being moved by the same outward movement of the leaves into engagement with the back part of the opening in the keeper plate. Thus it will be seen that the latching means firmly wedges itself in the keeper opening to prevent substantially all rattling. To release or open the door, the latching means is longitudinally retracted or slid in the direction of its length by operating the retracting lever 36 directly or 10 by operating roll back 39 by means of an outside handle (not shown) adapted to engage in the square aperture 48 provided in the roll back, roll back 39 in turn engaging and operating the retracting lever to longitudinally retract the latching means. 15

In assembling the latching means, the leaves are first assembled with the abutment bar and these parts then slid over the forward end of the supporting bar. The abutment bar is made slightly resilient so as to hold the leaves in engagement with the round head of the supporting bar and at the same time allow for the movement of the abutment bar by the leaves. 25

It is to be understood that the invention is not limited to the exact arrangement disclosed and that various modifications can be made without departing from the scope of the invention as defined in the appended 30 claims.

What is claimed is:

1. A latch comprising expansible latching means swingable to latching position and slideable to unlatched position. 40
2. A latch comprising an expansible and slideable keeper-engaging latching member, said member swinging to latching position and sliding to unlatched position. 45
3. A latch comprising latching means swingable and slideable on the same axis, said latching means swinging to latching position and sliding to unlatched position. 50
4. A latch comprising latching means swingable and slideable on the same axis, said latching means swinging transversely of said axis to latching position and slideable longitudinally of said axis to unlatched position. 55
5. The combination, with rigid keeper means, of normally projecting expansible latching means movable without longitudinal retraction to latched position within the keeper means, and means for retracting said latching means. 60
6. A latch comprising normally projecting latching means swingable on an axis extending longitudinally thereof to latching position, said latching means slideable on such longitudinal axis to unlatched position. 65
7. A latch comprising normally project-

ing latching means movable transversely on an axis extending longitudinally thereof to latched position, said latching means movable longitudinally of said longitudinal axis to unlatched position. 70

8. In a latch, a latch member comprising opposed elements movable transversely of a part of said member to latching position, said member being movable longitudinally to unlatched position. 75

9. A latch comprising normally projecting latching means movable without longitudinal retraction in a certain plane to latching position, said latching means being movable to unlatching position by movement in 80 a line substantially at right angles to the plane of movement which effects latching. 85

10. In a latch, a latch member comprising a part movable transversely of the latch member to latching position, said member being movable longitudinally to unlatched position. 90

11. In a latch, a latch member comprising a part movable transversely to an axis extending longitudinally of the latch member to latching position, said member being movable longitudinally to unlatched position. 95

12. In a latch, latching means adapted to be projected and retracted on an axis extending longitudinally thereof, said latching means comprising means movable transversely of its longitudinal axis to latching position. 100

13. In a latch, latching means adapted to be projected and retracted on an axis extending longitudinally thereof, said latching means comprising means rotatable on the longitudinal axis of said latching means to latching position, and means operable by such rotatable means adapted to be extended laterally of such rotatable means. 105

14. In a latch, latching means adapted to be projected and retracted on an axis extending longitudinally thereof, said latching means adapted to be contracted and expanded on the longitudinal axis thereof, said latching means movable to latching position while in the projected position. 110

15. The combination, with keeper means, of latching means adapted to be projected and retracted on an axis extending longitudinally thereof, said latching means adapted to be projected and retracted laterally of the longitudinal axis of said latching means, said latching means normally held in laterally projected position and adapted to be laterally retracted to engage within the keeper means and then laterally projected to hold the latching means against rattling in the keeper means. 115

16. A latch comprising latching means adapted to be projected and retracted laterally and longitudinally, said latching means normally held in laterally and longi-

- tudinally projected positions, said latching means movable laterally to latching position and movable longitudinally to unlatched position.
17. The combination, with keeper means, of latching members and an abutment member adapted to be projected and retracted laterally and longitudinally, the latching and abutment members movable into engagement with said keeper means, said latching and abutment members being laterally and longitudinally projected when engaged in the keeper means, said members being wedged against movement in said keeper means.
18. A latch comprising a supporting bar, a latching element mounted for sliding and swinging movement on said bar, and means operable by said latching element movable laterally of said bar.
19. A latch comprising a supporting bar, opposed latching elements mounted for sliding and swinging movement on said bar, and an abutment bar operable by said latching elements movable laterally of said supporting bar.
20. A latch comprising a supporting bar, opposed latching elements mounted for sliding and swinging movement on said bar, means for normally holding said latching elements in laterally projected position, and means operable by said latching elements movable laterally of said supporting bar.
21. A latch comprising a latching element, and an abutment bar, said latching element and abutment bar movable laterally and longitudinally, initial longitudinal movement of the abutment bar being transmitted to the latching element to move it longitudinally and initial lateral movement of the latching element being transmitted to the abutment bar to move it laterally.
22. A latch comprising opposed latching elements swingable to latching position and slideable to unlatched position, and abutment means movable laterally of said latching elements.
23. A latch comprising opposed latching elements swingable to latching position and slideable to unlatched position, and abutment means operable by said latching elements movable laterally thereof.
24. A latch comprising opposed latching elements swingable to latching position and slideable to unlatched position, and abutment means carried by said latching elements movable laterally thereof.
25. A latch comprising a casing, a supporting bar carried by said casing, opposed latching elements swingably and slidably mounted on said supporting bar, and abutment means movable laterally of said latching elements.
26. A latch comprising a casing, a supporting bar carried by said casing, opposed latching elements swingably and slidably mounted on said supporting bar, and abutment means carried by said latching elements movable laterally of said supporting bar.
- latching elements swingably and slidably mounted on said supporting bar, and abutment means carried by said latching elements movable laterally by said latching elements.
27. The combination, with rigid keeper means, of normally projecting latching means movable without longitudinal retraction to latched position within the keeper means, said latching means movable laterally within the keeper means to wedge the latching means against movement in the keeper means, and means for retracting said latching means.
28. In a latch, latching means adapted to be projected and retracted on an axis extending longitudinally thereof, said latching means adapted to be contracted and expanded on the longitudinal axis thereof, said latching means movable to latching position while in the projected position, means normally holding said latching means in projected position, and means normally holding said latching means in expanded position.
29. In a latch, latching means adapted to be projected and retracted on an axis extending longitudinally thereof, said latching means adapted to be contracted and expanded on the longitudinal axis thereof, said latching means movable to latching position while in the projected position, and means for retracting said latching means.
30. In a latch, latching means adapted to be projected and retracted on an axis extending longitudinally thereof, said latching means adapted to be contracted and expanded on the longitudinal axis thereof, said latching means movable to latching position while in the projected position, resilient means normally retaining said latching means in the projected position, resilient means normally retaining said latching means in expanded position, and means for retracting said latching means.
31. A latch comprising a supporting bar, latch members mounted for sliding and swinging movement on said supporting bar, and an abutment bar carried by said latch members and operable thereby, said abutment bar holding said latch members in engagement with said supporting bar.
32. A latch comprising a supporting bar provided with a rounded portion, latch members mounted for sliding and swinging movement on said supporting bar, each latch member provided with a rounded portion engaging the rounded portion of said supporting bar, and an abutment bar connected to said latch members and operable thereby, said abutment bar holding the rounded portions of said latch members in engagement with the rounded portion of said supporting bar.
33. A latch comprising a supporting bar

- provided with a circular bead, latch members mounted for sliding and swinging movement on said supporting bar, each latch member provided with an arcuate portion 5 and a substantially straight portion, said latch members mounted on said supporting bar so that the arcuate portions thereof engage the circular bead of said supporting bar with the substantially straight portions 10 of the latch members divergent, and an abutment bar connected to the arcuate portions of said latch members, said abutment bar holding the latch members in engagement with said supporting bar.
- 15 34. A latch comprising a casing, a supporting bar carried by said casing, said supporting bar provided with a circular bead, latch members mounted for sliding and swinging movement on said supporting bar, each latch member provided with an arcuate 20
- portion and a substantially straight portion, said latch members mounted on said supporting bar so that the arcuate portions thereof engage the circular bead of said supporting bar with the substantially straight 25 portions divergent, spring means for normally causing said straight portions of said latch members to diverge, an abutment bar connected to the arcuate portions of said latch members, said abutment bar holding 30 the latch members in engagement with said supporting bar, spring means engaging said abutment bar normally holding said abutment bar and latch members in longitudinally projected positions, and means engaging 35 said abutment bar for retracting said abutment bar and said latch members.

In testimony whereof I hereunto affix my signature.

FRANCIS M. VANDERVOORT.
